UNITED STATES PATENT OFFICE

150,457

DESIGN FOR A MICROPHONE UNIT OR THE LIKE AND PEDESTAL THEREFOR

Stewart W. Pike, Audubon, N. J., assignor to
Radio Corporation of America, a corporation of
Delaware

Application November 6, 1946, Serial No. 134,554

Term of patent 7 years

(Cl. D26—14)

To all whom it may concern:

Be it known that I, Stewart W. Pike, a citizen of the United States and a resident of Audubon, in the county of Camden and State of New Jersey, have invented a new, original, and ornamental Design for a Microphone Unit or the like and Pedestal therefor, of which the following is a specification, reference being had to the accompanying drawing, forming a part thereof.

Figure 1 is a perspective view of a microphone unit or the like and pedestal therefor showing my new design;

Figure 2 is a side elevational view thereof with the microphone unit inclined at an angle in one direction with respect to the vertical axis of the pedestal;

Figure 3 is a side elevational view thereof with the microphone unit inclined at an angle in another direction with respect to the vertical axis of the pedestal; and

Figure 4 is a top plan view.

I claim:

The ornamental design for a microphone unit or the like and pedestal therefor, substantially as shown.

STEWART W. PIKE.
